RODNEY G. RICHARDSON, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

RELAY SYSTEM

Application filed September 3, 1931. Serial No. 561,013.

The present invention relates in general to relay systems and the main object of the invention is the provision of a new and improved counting relay chain.

5 According to a particular feature of the invention, the relays of the counting relay chain are operated by the charging or discharging current of a condenser. This arrangement simplifies the operating and holding circuits for the counting relays and also permits the use of relays having only a single winding.

An understanding of other features of the invention and the detailed operation of the same may be had by a perusal of the following specification when read in connection with the accompanying drawing comprising Figs. 1 and 2, which show by means of the usual schematic diagram two embodiments 20 of the present invention.

Fig. 1 of the drawing discloses a counting relay arrangement in which the counting relays are operated by the discharge current of a condenser. This system may be employed in connection with a telephone system, conductors 1 and 2 being an incoming line terminating in an impulse relay 3, whereas 8 is the usual slow-to-release holding relay.

30 Fig. 2 shows a modification of the invention in which only single-wound counting relays are used and in which impulses are received over an impulse conductor 51 and in which 50 is the hold conductor over which the release of the counting relays is controlled.

The detailed operation of the modifications shown in the drawing will now be explained. Only the operating and control circuits of the counting relays have been shown, but it is to be understood that these relays also have other contacts which are used to complete the desired circuits dependent upon the number of impulses received.

45 When the equipment shown in Fig. 1 of the drawing is seized over the incoming line comprising conductors 1 and 2, the impulse receiving relay 3 operates over the loop circuit and at armature 4 and its working contact completes an obvious circuit for the

slow-to-release relay 8. At armature 5 and its working contact it completes a charging circuit for condenser 7 including the resistance 6 which is provided to limit the charging current of the condenser to a value which will not be detrimental to the spring contacts. Relay 8 operates and at armature 9 and its working contact connects ground to the hold conductor 10, thereby preparing the locking circuits of the counting relays. This ground is also extended through armatures 23, 27, 17, and 14 and their respective resting contacts, winding of relay 11, to battery. Relay 11 operates and at armature 12 and its working contact prepares the operating circuit for the first counting relay 13.

When the impulses are transmitted, the incoming loop circuit over conductors 1 and 2 is intermittently opened at the impulse sender, thereby causing relay 3 to release a corresponding number of times. At the first release of relay 3 it opens the circuit of relay 8 at armature 4 and its working contact but relay 8 is made slow-to-release by a copper slug on the heel end of its core and, therefore, remains operated throughout the impulse series. At armature 5 and its working contact, relay 3 opens the charging circuit of condenser 7 and at the resting contact of this armature it completes a discharging circuit for the condenser extending from battery, condenser 7, armature 5 and its resting contact, armature 12 and its working contact, lower winding of relay 13 to battery. The condenser 7 discharges over this circuit and the discharge current flowing through the lower winding of relay 13 operates this relay.

Relay 13 in operating, at armature 14 and its resting contact opens the circuit of relay 11 and at the working contact of this armature it completes the holding circuit from conductor 10 to the upper winding of relay 13. At armature 15 and its working contact it prepares the operating circuit for the succeeding counting relay 16.

At the end of the first interruption, relay 3 again operates and at armature 5 and its working contact again completes the charging circuit for condenser 7. At armature 4

and its working contact it again completes the circuit for the slow-to-release relay 8 to maintain this relay operated. When relay 3 releases at the beginning of the succeeding interruption the discharging circuit for condenser 7 is completed through armature 15 and its working contact through the lower winding of the succeeding relay 16. Relay 16 operates and at 10 armature 17 and its resting contact it opens the locking circuit of relay 13 and at the working contact of this armature it completes its own locking circuit from ground on the hold conductor 10. At armature 18 15 and its working contact it prepares the discharging circuit to the succeeding counting relay 19. At the end of the impulse, relay 3 again energizes and at armature 5 and its working contact again completes the 20 charging circuit for condenser 7.

Relays 19 and 22 and the remaining counting relays, if more are required, are operated in the same manner responsive to successive deenergizations of impulsive relay 3. Each relay is energized over its lower winding by the discharge current from condenser 7 and locks itself energized to the hold conductor 10, at the same time opening the locking circuit of the preceding 25 counting relay and allowing it to release. Each counting relay upon operating also prepares the operating circuit to the lower winding of the succeeding counting relay. Thus only one counting relay will remain 30 energized at the end of the impulse series and this counting relay, through contacts not shown on the drawing, may complete the desired circuit depending upon the number of impulses in the impulse train.

40 The successful operation of the arrangement depends upon the fact that practically all of the condenser discharge current is required to operate the connected counting relay, so that little or no current will flow 45 through the winding of the succeeding counting relay when the discharge circuit is extended to its winding. This result is obtained by selecting the proper size condenser with regard to the resistance of the 50 windings of the counting relays. The lower armatures of the relays may be adjusted to operate last so that the circuit to the succeeding counting relay will not be closed until the connected counting relay has fully 55 operated.

The counting relays are restored by breaking the loop circuit over conductors 1 and 2, thereby causing relay 3 to release. At armature 4 and its working contact, relay 3 60 opens the circuit of slow-to-release relay 8 which releases after an interval and at armature 9 and its working contact removes ground from the hold conductor 10, thereby allowing the operated counting relay to 65 release.

The modification shown in Fig. 2 of the drawing is arranged to operate in connection with a system in which ground impulses are transmitted over a single conductor, namely conductor 51. Conductor 50 extends to the hold circuit over which ground is supplied as long as the equipment is in operation and from which ground is removed to release the counting relay chain. 70 In this modification, the condenser 52 is normally fully charged over a circuit from battery, condenser 52, armature 55 and its resting contact, resistance 53 to ground. Resistance 53 is provided to limit the charging current of the condenser to a value 80 which will not be harmful to the relay spring contacts.

When the counting relay switch is seized for operation, ground is connected to hold conductor 50 thereby bringing about the operation of relay 56. Relay 56 at armature 57 and its working contact connects ground to conductor 72, thereby preparing the locking circuits of the counting relays 58 to 70, inclusive. When impulses are received over conductor 51, relay 54 responds to each ground impulse, and when it energizes responsive to the first impulse it completes a discharging circuit for condenser 52 extending from battery, condenser 52, armature 55 and its working contact, armatures 69, 66, 63, and 60 and their respective resting contacts, winding of relay 58, to battery. Condenser 52 discharges over this circuit and the discharge current through the winding of relay 58 operates this relay. In operating, relay 58, at armature 59 and its working contact, completes a locking circuit for itself extending from ground at armature 57 of relay 56, conductor 72, armatures 71, 68, 65, and 62 and their respective resting contacts, armature 59 and its working contact, winding of relay 58 to battery. At armature 60 and its resting contact, relay 58 opens the discharging circuit for condenser 62 and at the working contact of this armature prepares a discharging circuit through the winding of relay 61. Armature 60 and the corresponding armatures of the other counting relays are adjusted to operate last so that the locking contacts of the relays will be closed before the operating circuits are opened. At the end of the impulse, relay 54 releases and at armature 55 and its resting contact again completes the charging circuit for condenser 52 over resistance 53. 100

At the beginning of the succeeding impulse, relay 54 again operates and at armature 55 and its working contact completes the discharging circuit for condenser 52 extending from battery, condenser 52, armature 55 and its working contact, armatures 69, 66, and 63 and their respective resting contacts, armature 60 and its working contact, winding of relay 61 to battery. The 110 115 120 125 130

condenser 52 discharges over this circuit and the discharge current through the winding of relay 61 operates this relay. At armature 62 and its resting contact, relay 61 opens 5 the locking circuit of the first counting relay 58 and at the working contact of this armature completes its own locking circuit from ground on conductor 72. At armature 63 and its resting contact it opens the discharge 10 circuit through the winding of relay 61 and at the working contact of this armature it prepares a discharge circuit for the condenser through the winding of the succeeding counting relay 64. At the end of the 15 second impulse, relay 54 again releases and at armature 55 and its resting contact again completes the charging circuit for condenser 52.

The succeeding relays 64, 67, 70, and the 20 remaining relays in the chain, if more are provided, are operated in the same manner as pointed out above for relays 58 and 61. Each relay upon operating prepares the discharge circuit of condenser 52 through the 25 winding of the succeeding relay and at its upper armature completes a locking circuit for itself, at the same time opening the locking circuit of the preceding counting relay. Thus at the end of the impulse train only 30 the proper counting relay remains operated to effect a closure of the desired circuit over contacts not shown on the drawing. When it is desired to open the completed circuit and to release the counting relay chain, 35 ground is removed from the hold conductor 50, thereby bringing about the release of relay 56. Relay 56 at armature 57 and its working contact disconnects the holding ground from conductor 72, thereby allowing 40 the operated counting relay to restore to normal.

Although only two modifications of the invention have been disclosed in the drawing, it will be at once apparent to those 45 skilled in the art that many changes and modifications may be made without departing from the spirit of the invention. It will also be at once apparent that the circuits may be so arranged that the counting relays 50 are operated by the charging current of the condenser instead of the discharging current in which case the condenser will be discharged between impulses.

What is claimed is:

- 55 1. In combination, a plurality of counting relays, a condenser, an impulse receiving relay, a charging circuit for said condenser including contacts on said impulse receiving relay, and a discharging circuit for said condenser controlled by said impulse receiving relay to successively operate said counting relays responsive to received impulses. 60
2. In combination, a plurality of counting relays, a condenser, a charging circuit for said condenser, a discharging circuit for 65
- said condenser over which said counting relays are operated, the operation of each relay extending the circuit to the succeeding relay, and an impulse receiving relay for alternately closing said charging and discharging circuits responsive to received impulses, each discharge of said condenser operating one of said counting relays. 70
3. In combination, a plurality of counting relays, a condenser, means responsive to received impulses for charging and discharging said condenser, once for each impulse, an operating circuit for said counting relays over which the relays are operated one at a time responsive to the condenser discharge current, and means responsive to the operation of each relay for extending the operating circuit to the succeeding relay. 75
4. The combination with a plurality of counting relays of means including a condenser for operating said relays responsive to received impulses, and circuit connections between said condenser and said relays for causing said relays to be operated in turn, one for each impulse. 80
5. In combination, a plurality of counting relays, an operating circuit for said relays, contacts on each relay for extending said operating circuit to the succeeding relay, and a condenser in said circuit for causing the operation of each relay in turn responsive to received impulses. 85
6. The combination with a series of counting relays of a condenser, means for alternately charging and discharging said condenser, and means for successively operating said counting relays by the condenser discharge currents. 90
7. In combination, a plurality of counting relays, a condenser, means for charging said condenser, an operating circuit extending to said relays, means responsive to received impulses for intermittently discharging said condenser over said circuit to operate said relays, and means controlled by each relay for locking itself energized, for opening the locking circuit of the preceding relay, and for extending the operating circuit to the succeeding relay. 100
8. In combination, a plurality of counting relays, an impulse receiving relay, a condenser, means responsive to the operation of said impulse receiving relay for completing a charging circuit for said condenser 110 and for preparing a discharging circuit including the first of said counting relays, means responsive to the deenergization of said impulse receiving relay responsive to a received impulse for completing said discharging circuit to operate said first counting relay, and means responsive to the operation of said first counting relay for locking itself energized, for opening said discharging circuit, and for preparing a discharging 115
- 120
- 125
- 130

circuit including the second of said counting relays.

9. A counting relay switch comprising a line relay, a release relay, and a plurality of 5 counting relays, an incoming loop circuit for controlling said line relay, means responsive to the seizure of said switch over said loop circuit for operating said line and release relays, means controlled by said release re- 10 lay for preparing an operating circuit to said counting relays, a condenser, a charging circuit for said condenser completed by the operation of said line relay, and means responsive to impulses received over said 15 loop circuit for intermittently discharging said condenser over said operating circuit to successively operate said counting relays, one for each received impulse.

10. In a counting relay switch, a line re- 20 lay, a plurality of counting relays, means responsive to the operation of said line relay for preparing an operating circuit and a locking circuit for said counting relays, a condenser, a charging circuit for said con- 25 denser completed when said line relay is operated, means for discharging said condenser over said operating circuit to successively operate said counting relays responsive to receive impulses, and contacts on each count- 30 ing relay for locking itself energized to said locking circuit, for opening the locking circuit to the preceding counting relay, and for extending said operating circuit to the suc- 35 ceeding counting relay.

35 11. In combination, a plurality of count- ing relays, an impulse relay, a condenser, a normally closed charging circuit for said condenser, an operating circuit extending to said counting relays, means responsive to 40 the intermittent operation of said impulse relay responsive to received impulses for dis- charging said condenser over said operating circuit to successively operate said counting relays, one for each impulse received, and 45 means controlled by each counting relay for releasing the preceding counting relay.

12. In combination, a plurality of count- 50 ing relays, an impulse relay, a condenser, a normally closed charging circuit for said condenser, an operating circuit extending to said counting relays, means responsive to the intermittent operation of said impulse relay responsive to received impulses for dis- 55 charging said condenser over said operating circuit to successively operate said counting relays, one for each impulse received, a locking circuit for said counting relays, and contacts on each counting relay for locking it- 60 self energized over said locking circuit, for opening the locking circuit to the preceding counting relay, for opening its own operating circuit, and for extending the operating circuit to the succeeding counting relay.

13. In combination, a plurality of count- 65 ing relays, an operating circuit for said re-

lays, contacts on each relay for extending said operating circuit to the succeeding relay, an energy-storing device in said circuit large enough to store sufficient energy to operate one relay but not two, and means for 70 renewing the energy stored in said device each time a relay is operated.

14. In combination, an impulse counter comprising a plurality of counting relays, an operating circuit for said relays, contacts 75 on each relay for transferring said circuit to the succeeding relay, an impulse storer included in said circuit, means for storing energy in said storer each time an impulse is received, and means for utilizing the en- 80 ergy stored by each impulse for operating one of said relays over said circuit.

15. In combination, a counting system comprising a plurality of counters and an energy storing device, means responsive to 85 received impulses for storing corresponding impulses in said storing device, and means for utilizing the stored impulses to operate said counters in turn, only one counter be- 90 ing operated for each stored impulse.

16. In a system for counting received im- 95 pulses, a plurality of counters, means for con- verting each received impulse into stored en- ergy, means for utilizing the energy stored by each impulse to operate one of said 100 counters, and means controlled by each counter for substituting the succeeding counter for itself so that the succeeding counter is operated by the energy stored by the succeeding impulse.

17. In combination, a line relay having an armature, a plurality of counting relays, a closed circuit for said line relay, an energy storing device, a circuit over which energy is stored in said device including a front 105 contact of said armature, an operating circuit extending to said counting relays, a back contact for said armature for connecting said device to said operating circuit whereby the energy stored in said device is utilized to operate one of said counting re- 110 lays each time said line relay releases responsive to an interruption of its circuit, and contacts on each counting relay for extending said operating circuit to the succeeding counting relay.

In witness whereof, I hereunto subscribe my name this 31st day of August, A. D. 1931.

RODNEY G. RICHARDSON.
